THREAD DRAWING DEVICE

Nikolaus Deutsch, Budapest, Hungary

Application July 8, 1930, Serial No. 466,606,
and in Hungary February 3, 1930

3 Claims. (Cl. 112—78)

In woven fabrics perforated places (open work) are produced by a number of warp threads being forced downwards with a suitably formed pusher comprising a blunt-ended needle and cut off by means of a pivoted cutter. In this operation the material has to be kept taut, as otherwise the pusher will not work reliably.

Thread drawing machines are known, in which grippers are used, which perform a lateral motion besides the motion in the forward feeding direction, and the material is stretched over parallel bars on the throat plate. This stretching is however insufficient, as the material to be perforated offers a relatively great resistance.

15 In these thread drawing devices, in which the downwardly forced threads are cut off by means of a pivoted cutter and the lower face of the throat plate has a circular recess, one edge of the pusher hole acts as the counter blade.

20 In such arrangements, for reliably cutting through the threads the lower circular recess in the throat plate must be ground so as to correspond to the sweep of the cutter, as otherwise the threads will not be cut reliably between the 25 rocking cutter and the stationary counter cutting edge of the throat plate. This disadvantage is not only apparent in new machines owing to the difficulty of grinding, but more particularly when the circular recess in the throat plate 30 has become worn. An adjustment of the cutter is only effected by the helical spring, but the cutting edge of the cutter cannot adapt itself to the inequalities of the circular recess in the throat plate in the lateral direction.

35 The present invention overcomes these disadvantages.

In the accompanying drawing a constructional example of the invention is shown.

Fig. 1 being a side elevation partly in section, 40 Fig. 2 a front elevation partly in section, Fig. 3 a longitudinal section through the throat plate to an enlarged scale and

Fig. 4 a front elevation partly in section of the cutter head with the cutter to an enlarged scale.

Fig. 5 is a front elevation partly in section of a modification of the cutter head and cutter.

The throat plate *d* positioned between the feet *a* of the presser bar *b* above the feed dog *c* has on its upper surface an inclined raised part *e* having two ribs *e*¹, one on each side of an opening *e*¹ in the throat plate and which hold the material taut while it is being fed forward, said ribs being inclined upwards in the direction in which the fabric is fed forward. In the throat

plate the opening *e*¹ for the passage of the pusher is widened in such a manner that the lower end of the additional presser foot *e*³ which is fixed to the presser bar *b* projects into this opening. The lower surface of the throat plate is made 60 arcuate. Against this arcuate surface the cutter *n* in the cutter holder *g*, *g*¹ is pressed by means of the helical spring *h*, the lower sharp edge *e*² of the opening *e*¹ acting as the counter cutting edge for the cutter *n*. The pusher *k* which is 65 fixed in the pusher bar *i* forces the longitudinal threads of the material downwards, which are cut off in a known manner by means of the cutter *n*. The material *m* is guided between the feet *a* of the presser bar and under the presser foot *e*³ 70 which enters the opening *e*¹ and holds the tensioned material in position as the pusher descends.

The cutter holder *g*, *g*¹ swings to and fro in a known manner and the cutter *n* is pressed against 75 the arcuate surface *e*⁴ of the throat plate *d*. In the head *g*¹ of the cutter holder is a slot *o* into which the cutter blade *n* is loosely inserted. The lower end *n*¹ of the cutter blade has the shape of an arc, so that the cutter blade sets itself automatically with its cutting edge against the counter cutting edge laterally at a certain angle, if the arcuate surface in the throat plate is not correctly ground or is worn in places. The cutter blade may also be arranged to turn about a pin *n*²² 80 for obtaining the same result, as shown in Fig. 5. In this case the lower end *n*²¹ of the cutter blade *n*¹¹ does not bear against the bottom of the slot *o* and consequently need not have the shape of a circular arc but may be straight as shown. The 85 lower end *n*²¹, however, must be spaced from the bottom of the slot *o* by an amount sufficient to enable the blade *n*²¹ to turn about the pin *n*²² to set itself automatically with its cutting edge against the counter cutting edge in a similar manner to the cutter blade *n* in Fig. 4.

What I claim is:

1. A device for drawing threads from woven fabrics, comprising a throat plate having an opening therein, means for feeding the fabric forward over the throat plate, two ribs on the throat plate, one on either side of the said opening and inclined upwards in the direction in which the fabric is fed forward, means for stretching the fabric tautly over the said ribs, a cutter head capable of swinging to and fro with respect to the throat plate, said cutter head having a slot therein, a cutter capable of oscillating laterally in the said slot and a counter cutting 110

edge on the throat plate for coating with the said cutter, as and for the purpose set forth.

2. A device for drawing threads from woven fabrics, comprising a throat plate having an opening therein, means for feeding the fabric forward over the throat plate, two ribs on the throat plate, one on either side of the said opening and inclined upwards in the direction in which the fabric is fed forward, means for stretching the fabric tautly over the said ribs, a cutter head capable of swinging to and fro with respect to the throat plate, said cutter head having a slot therein, a cutter having its lower edge in the shape of an arc and mounted loosely in said slot so as to be capable of oscillating therein and a counter cutting edge on the throat plate for co-acting with the said cutter, as and for the purpose set forth.

3. A device for drawing threads from woven fabrics, comprising a throat plate having an opening therein, means for feeding the fabric forward over the throat plate, two ribs on the throat plate, one on either side of the said opening and inclined upwards in the direction in which the fabric is fed forward, means for stretching the fabric tautly over the said ribs, a cutter head capable of swinging to and fro with respect to the throat plate, said cutter head having a slot therein, a pin in the said cutter head, a cutter mounted loosely on the said pin so as to be capable of oscillating in said slot and a counter cutting edge on the throat plate for co-acting with the said cutter, as and for the purpose set forth.
